UNITED STATES PATENT OFFICE

2,031,370

AUTOGRAPHIC REGISTER

Louis Jensen, Chicago, Ill., assignor to United Autographic Register Co., Chicago, Ill., a corporation of Illinois

Continuation of application Serial No. 709,505, filed February 2, 1934. This application filed November 17, 1934, Serial No. 753,551

11 Claims. (Cl. 282—21)

This invention relates particularly to duplicating machines and to an improved register casing and means for initially advancing stationery from under a tear-off bar after a tearing operation. 5 Preferably, the stationery is provided with register perforations and the register has yieldingly urged register pins to arrest the advance of the stationery when withdrawn manually a form length.

10 The primary object of the invention is to provide a simple initial feed device for a hand pull-out machine of improved construction, wherein the stationery will be automatically released and advanced by rotation of the feed roll shaft.

15 The present application is a continuation of my application Ser. No. 709,505, filed February 2, 1934.

The invention is illustrated in a preferred embodiment in the accompanying drawings, in which—

20 Fig. 1 is a broken plan view of an autographic register embodying the invention; Fig. 2, an end elevational view of the same; Fig. 3, a broken longitudinal sectional view, taken as indicated at line 3 of Fig. 1; Fig. 4, a broken sectional view, 25 taken as indicated at line 4 of Fig. 1; Fig. 5, a broken longitudinal sectional view, taken as indicated at line 5 of Fig. 1; Fig. 6, a broken plan view of the cam springs and supporting bar; Fig. 7, a longitudinal sectional view taken as indicated at line 7 in Figs. 8 and 9 showing a modified register embodying the invention; Fig. 8, a transverse sectional view taken as indicated at line 8 of Fig. 7; Fig. 9, a broken plan view from below showing the initial feed mechanism; Fig. 10, a broken 30 front elevational view of the register frame with the casing removed; Fig. 11, a broken sectional view taken as indicated at line 11 of Fig. 9; and Fig. 12, a broken sectional view taken as indicated at the line 12 of Fig. 9.

40 The invention is particularly adapted to small portable registers which may be made of sheet-aluminum. It will be understood that the stationery and metal are not drawn to scale in the accompanying drawings, which results in some distortion of the views.

In the construction illustrated in Figs. 1 to 6, A designates a casing provided with a bottom wall A', a top wall A² serving as a platen, a front end wall A³, and a carbon-roll holder A⁴; B, a skeleton cover forming a partial closure for the platen A² and provided at its front end portion with a tear-off bar B'; and C, an initial feed device.

The casing A is constructed substantially the same as the one described in my Patent Number 55 1,902,284 issued March 21, 1933. It serves as a

housing for a zig-zag folded packet of continuous-form stationery 10 which is led over the back of the platen A² and has its register perforations 11 engaged by register pins 12 beneath the tear-off bar B'. The register pins are shown mounted on 5 forwardly extending leaf springs 13 which are rigidly connected to a cross-member 14 mounted on the underside of the platen A². To the cross-bar 14 is rigidly connected a forwardly extending leaf spring 15, the purpose of which will be described below.

The skeleton cover B is arranged to snap over the casing A and may be conveniently removed to permit the stationery 10 to be led over the platen to the register pins in interleaved relation 15 with carbon strips (not shown) from the container A⁴. The tear-off bar B' may be rigidly connected to the cover B by means of rivets 16. Near the central portion of the tear-off bar, portions 17 of the bar are stuck upwardly to form 20 journals for a shaft 18 on which is rotatably mounted a knurled presser roll 19.

The initial feed device C is shown provided with a transverse shaft 20 which is journaled in the side walls of the register beneath the tear-off bar. 25 The shaft is provided with a mutilated feed roll 21 having a flat portion 22 presented to the roll 19 when the register pins 12 are engaging the perforations in the stationery. The shaft is further provided with a pair of cams 23 which are 30 provided with flat faces 24 which engage depending arms 25 connected to the leaf springs 13 by means of rivets 26. The cams 23 and feed wheel 21 are so arranged that during rotation of the shaft 20, the cams retract the pins 12 through 35 the medium of arms 25 just prior to the feed wheel 21 coming into engagement with the stationery and pressing it against the presser roll 19 to commence a feeding operation. As shown in Figs. 1 and 2, the shaft 20 may be provided with 40 a knob 27 for manual rotation of the shaft. As indicated in Figs. 2 and 5, the front wall A³ of the register has cut-away portions 28 to permit downward movement of the arms 25.

The shaft 20 is further provided with a cam 45 30 having a flattened face 31 which is acted upon by the forwardly extending leaf spring 15. The cam 30 is positioned so that the flattened portion of the feed wheel 21 is presented to the presser roll 19 when the register pins 12 are permitted 50 to spring upwardly by the cams 23.

In operation, it will be understood that the forms may be fed out as far as desired by merely rotating the knob 27. However, in the preferred operation, the knob 27 is rotated sufficiently to 55

retract the pins 12 and feed the stationery far enough to permit it to be grasped and manually withdrawn. In manually withdrawing the paper, the feed wheel 21 will rotate until its flattened 5 surface is presented upwardly and it will then be yieldingly held in that position through the action of spring 15 on cam 30. While in this position, the pins 12 will be permitted by the cam 23 to be yieldingly urged against the lower face of 10 the stationery 10 and upon engagement with register perforations 11, the advance of the stationery will be arrested and the completed form may be separated on the bar B'.

In the modification illustrated in Figs. 7-12 the 15 register mechanism is similar to that described above except that an improved register casing is provided for the platen frame, the feed wheel has two mutilated sections and is operated by centrally disposed ratchet mechanism. 20 The register casing comprises a lower portion 35 and an upper portion 36 which is hinged to the lower portion at 37 and overlaps the opposite side wall 38 of the lower portion with a flange 39 which serves to hold a carbon strip, or strips, 25 40 in interleaved relation with stationery strips 41. The upper portion of the casing 36 affords a skeleton cover 42 to provide access to the writing platen. The cover is shown provided at its front end with a transverse tear-off blade 43 equipped 30 with a housing 44 in which is mounted a presser roll 45. The register frame comprises a platen 46 equipped with integrally formed side walls 47 which are firmly connected to the bottom wall of the lower portion of the casing at 48. As will 35 be seen from Fig. 8, the outer casing is rounded so that a compartment 49 is provided for a carbon roll 50 from which the strips 40 may be drawn over the platen. The frame is further provided with a bottom wall 51 which provides a supply 40 compartment 52 for a zig-zag folded packet of stationery 53. The bottom wall is curved downwardly and joined to the bottom wall of the casing at its rear portion as indicated at 54 and its front end is curved upwardly as indicated at 55 45 and terminates at the front end of the platen 46. This construction provides an additional compartment 56 which may be used to store completed copies as shown in my above patent. The pair of abutments 57 and 58 are struck from the bottom wall 51 to permit operation of the initial feed 50 mechanism and prevent the pack 53 from coming in contact therewith.

As shown in Fig. 7, an extension 59 is hingedly connected at 60 to the rear of the platen 46 and provides journal members 61 for the guide roll 62. A narrow tray-like guide member 63 is placed in the compartment 52 to facilitate insertion and removal of a packet of stationery through the rear end of the machine after the cover has been 60 swung upwardly and the guide roll 62 swung up out of the way about the pivot 60. This member has a guide portion 64 at its rear end which is adjacent to the guide roll 52 and prevents more than a single set of strips from being drawn from the compartment at one time. The frame is further provided with the usual supporting bars 65 for the forwardly extending carbon-protecting aprons 66 as is well understood in the art.

The initial feed device is similar to that described above and has a transverse shaft 67 journalled in the side walls 47 of the frame beneath the tear-off bar 43. The shaft is provided with a rigidly connected feed wheel 68 having two mutilated portions 69, either of which is presented 70 towards the roll 45 when register pins 10 are free

to bear against the strips 41. The shaft is further provided with a pair of cams 71 having two flat faces which engage depending arms 72 which are riveted to the leaf springs 73. The cams 71 and feed wheel 68 are so arranged that when the shaft 5 is rotated the cams will retract the pins 10 prior to the unmutilated portion of the feed wheel coming into engagement with the stationery to begin a feeding operation.

The shaft 67 is further provided with a cam 74 10 having two flattened faces which are acted on by a forwardly extending leaf spring 75. The latter cam is positioned so that one of the mutilated portions of the feed wheels is urged to a position adjacent to the presser roll 45 when the register 15 pins are permitted to spring upwardly by the cams 71.

In order to facilitate operation of the feed shaft a U-shaped member 76 having a centrally disposed finger piece 77 is journalled on the shaft 20 67 and is equipped with a pawl 78 which is held in engagement with a ratchet wheel 79 fixedly mounted on the shaft 67. The pawl is acted upon by a spring 80 and an additional spring 81 is provided to urge the ratchet member upwardly into 25 the position shown in Fig. 7.

The operation of the mechanism is similar to that described above except that it is merely necessary for the operator to momentarily depress the finger piece 77 to feed out a form sufficiently to permit it to be grasped by hand and withdrawn until the next set of perforations are engaged by the register pins.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. An autographic register comprising: a casing having a platen over which a plurality of stationery strips provided with register perforations may be led; a tear-off bar near the front of said platen whereon the strips may be severed, a rotatable presser-roll mounted on said tear-off bar and adapted to engage the strips; register pins yieldingly urged into engagement with the register perforations in strips advanced over the platen; and an initial feed device for said strips comprising a transverse rotatable shaft provided with a mutilated feed wheel adapted upon rotation to press the strips against the presser-roll, cam-means for holding the register pins depressed while the strips are engaged by said feed wheel, and yielding means for holding the mutilated portion of the feed wheel adjacent to the strips when the register pins are released by said cam-means.

2. A duplicating machine comprising: a frame having a platen over which stationery strips having register perforations may be led; a yieldingly urged pin adapted to engage perforations in said strips to arrest the advance thereof; a rotatable feed-wheel having a portion of its circumference cut away for initially advancing the strips; yielding means for positioning the cut-away portion towards the strips when the pin is projected through a perforation in the stationery; and means for automatically retracting the pin from engagement with the strips upon rotation of the feed-wheel and prior to the advancing of said strips.

3. In a hand pull-out autographic register: a

frame having a platen over which stationery strips provided with register-perforations may be led; register-pins movably mounted on said frame and adapted to engage perforations in said strips; feed-means comprising a mutilated feed-wheel journaled in said frame and adapted upon rotation to retract said pins and to engage and advance said strips; and spring-means adapted to urge said register-pins into engagement with the strips and to urge the mutilated portion of the feed-wheel to a position adjacent to the strips to facilitate hand-withdrawal of the strips.

4. A mechanism as specified in claim 3, in which the feed-wheel has a shaft provided with cams, one of said cams having a flat-face diametrically opposed to the mutilated portion of the feed-wheel and acted upon by a finger of the spring-means, and the other cams being engaged by arms connected to the register-pins.

5. In a hand pull-out autographic register: a frame having a platen over which stationery strips provided with register-perforations may be led; a register pin movably mounted on said frame and adapted to engage perforations in said strips; feed-means comprising a feed-wheel journaled in said frame and adapted upon rotation to advance said strips; and a finger-operable ratchet-means centrally disposed near the front of said platen and adapted to rotate said feed-means.

6. Mechanism as specified in claim 5, in which the feed wheel is mounted on a shaft in the front of the frame and the ratchet means comprises a U-shaped member journaled on said shaft and is provided with spring-means for urging the finger member to its uppermost position.

7. Mechanism as specified in claim 5, in which the feed-wheel has two mutilated portions and spring-means for urging either of the mutilated portions of the feed-wheel to a position to facilitate hand-withdrawal of the stationery strips.

8. A hand pull-out autographic register comprising a casing having a skeleton cover hinged near the center of one side of said casing; a frame having a platen mounted in the casing so as to provide a carbon-roll compartment near one edge of said casing from which carbon strips may be led

over the platen; register pins movably mounted on said frame and adapted to engage perforations in stationery strips led over said platen in interleaved relation with said carbon strips; feed means comprising a mutilated feed-wheel journaled in said frame and adapted upon rotation to retract said pins and advance the stationery strips; and spring-means adapted to urge the mutilated portion of the feed wheel to a position to facilitate hand-withdrawal of said stationery strips.

9. Mechanism as specified in claim 8, in which the skeleton cover is provided with presser roll adapted to cooperate with mutilated feed-roll in initially advancing the strips.

10. Mechanism as specified in claim 8, in which the frame is provided with a supply compartment from which stationery strips may be drawn over the platen, a guide-roll is journalled in a bracket pivotally mounted on the rear of said platen, and a guide-tray is withdrawably positioned in said supply compartment to facilitate withdrawal of a supply of stationery and is equipped near its rear end with an upwardly extending bracket adapted to cooperate with said guide-roll in facilitating withdrawal of sets of strips from said compartment over the platen.

11. A duplicating machine comprising: a frame having a platen over which a plurality of continuous-form stationery strips provided with register perforations may be led; a yieldingly urged pin adapted to engage perforations in said strips and arrest the advance thereof; a tear-off blade near the front of said platen whereon the strips may be severed; and a feed device for initially advancing the stationery comprising a rotatable feed wheel having a portion of its circumference cut away, said feed wheel being mounted to engage frictionally and advance the strips less than a form length during one revolution, means for urging the cut away portion of the wheel towards the strips when the pin is projected through a perforation in the stationery, and means for automatically retracting the pin from engagement with the strips upon rotation of the feed wheel and prior to the advancing of said strips.

LOUIS JENSEN.
